UNITED STATES PATENT OFFICE.

FERNANDO ROQUE ELIZONDO, OF MEXICO, MEXICO.

DEVICE FOR AUTOMATICALLY ANNOUNCING ORDERS AND DANGERS TO MOVING TRAINS.

1,347,538.

Specification of Letters Patent.

Patented July 27, 1920.

Application filed November 15, 1917. Serial No. 202,212.

To all whom it may concern:

Be it known that I, FERNANDO ROQUE ELIZONDO, a citizen of the Republic of Mexico, and a resident of Mexico city, Mexico, have 5 invented new and useful Devices for Automatically Announcing Orders and Dangers to Moving Trains, of which the following is a specification.

This invention relates to a device which 10 announces automatically stop signals to the engineer of a moving train and which automatically applies the air brakes in case the engineer should not heed the stop signals immediately.

15 It is therefore an object of this invention to provide a device which may be adapted to the engine of a train or to any other kind of vehicle moving on rails and provided with air brakes, and which indicates 20 automatically the places where the train is to stop.

It is also an object of this invention to provide a device which announces stop signals to the engineer of a train by the blowing 25 of a whistle and by a red danger signal shown, and which permits the engineer to apply the air brakes so as to bring the train to a stop.

It is finally an object of this invention to 30 provide a device which will automatically apply the air brakes of a train after passing a stop signal if the engineer should not for any reason notice the previous blowing of the whistle and the red signal shown, and 35 which will register the number of stops made on a numbered dial connected with said device.

The invention (in a preferred form) is illustrated in the drawings and hereinafter 40 more fully described.

In the drawings:

Figure 1 is a general view of the device.

Fig. 2 shows the interior mechanism of the device.

45 Fig. 3 is a section taken on line 3—3 of Fig. 2.

Fig. 4 is a detailed view of the valve which opens and closes the tube of the air brake.

50 Fig. 5 is a detail section of the same valve.

Fig. 6 is a detail view of the toothed segment which winds up the spring of the mechanism.

55 Fig. 7 is a front elevation of the toothed segment, showing the stops.

Fig. 8 is an enlarged detail view of the lever which operates the segment.

Fig. 9 is a detail view of the pawl which engages the segment.

Fig. 10 shows the form of the double 60 armed lever which disengages the pawl shown in Fig. 9.

Fig. 11 is an enlarged front elevation of the announcing or signaling mechanism.

Fig. 12 is a rear view of the mechanism. 65

Fig. 13 is a section taken through said mechanism.

Fig. 14 is an enlarged detail view of the pawl which engages the signaling plate.

Fig. 15 is a fragmentary detail view of 70 the operating rod.

Fig. 16 is a detailed view of the double framed carriage which actuates the operating rod.

Fig. 17 is a top plan view of the same carriage. 75

Figs. 18 and 19 indicate two different forms of the blocks provided to lift the inner frame of the carriage.

Fig. 20 illustrates the manner in which the 80 wheel engages the block in the inner carriage.

As shown in the drawings, the device consists of a circular casing 1, the top or front of which is closed by a lid 2 screwed over 85 the sides of the casing. Substantially in the center of casing 1 is another casing 3, in the bottom of which, but independently therefrom, is provided a gear wheel 4, the top of said casing 3 being formed by a ratchet 90 wheel 5. In the interior of said casing there is a spring 3^a, and which is connected both with the gear wheel 4 and the ratchet wheel 5. The casing 3 rotates on a shaft 6 which moves in bearings provided in the bottom 95 of casing 1 and in the plate 7, which plate is fastened to the bottom of casing 1 by means of brackets 8. The spring in casing 3 is adapted to be wound up, and the tension is maintained by a suitable pawl which engages the ratchet wheel 5. The gear wheel 4 is connected by means of a plurality of gear wheels 9, 10, 11, 12 and 13 with a regulator 14 which serves to regulate the movement of the valve opening and closing 100 mechanism, as will be described hereafter.

The gear wheel 4 engages a gear wheel 15 at the bottom of the valve casing 16. This valve casing is perforated longitudinally, as will be seen in Figs. 4 and 5, and tubes 110

17 and 18 are provided at opposite ends of this perforation, which tubes project through the sides of casing 1. The valve casing 16 is secured to the interior side of casing 1 by means of screws or bolts. A conical member 19 is fastened to the gear wheel 15, said conical member entering a conical perforation in the casing 16 and being secured at the top of said casing by a plate 20, being furthermore provided with a laterally extending perforation 21 which corresponds with the perforation in casing 16, forming thereby a valve which may be opened or closed by the rotation of the gear wheel 15.

The superior extremity of the tube 17 is provided with a fitting 22, one outlet of which is connected with the air brake of the vehicle, and the other outlet with a whistle 23. The other tube 18 is connected at its inferior end with the compressed air chamber or with any other means for supplying the air which operates the air brakes.

The gear wheel 4, at the side opposite to the valve casing 16, engages the toothed segment 24, a detailed view of which is given in Figs. 6 and 7, which segment is pivotally attached to one side of the bottom plate of casing 1, and serves to wind up the spring in casing 3 by means of the gear wheel 4. This is obtained by the lever 25 (Fig. 8) pivotally mounted on one side of the casing 1 and provided with a spring 26 which tends to push the lever against the side of the casing 1. Said lever is connected by means of a cable with the handle 27 which on being pulled downwardly brings the lever to bear against the stud 28 mounted on the segment 24, and rotates the segment. On reaching its downmost position, the segment is held down by a pawl 29, shown in Fig. 9, which is mounted pivotally and engages the projection 30 also provided on said segment.

The pawl 29 is held in position by the spring 31 (Figs. 1 and 9) and actuated by means of a double armed lever 32 provided at the inferior inner side of casing 1, one arm of said lever having a rounded extremity which conforms with the concave form of the pawl 29 (Fig. 10). The opposite arm of the lever 32 is held down by a spring 33 over a perforation provided in the inferior part of the side of casting 1, through which perforation projects the superior extremity of a rod 34. This rod passes downwardly through a tube 35 secured by means of a flange 36 to the inferior part of the outside of casing 1. Said rod, within the tube 35, is provided at its upper end with a thrust plate 37 and at its inferior part with a buffer base plate 38 slideable vertically upon the rod 34, and separated by a spring 39 from the thrust plate 37 (Fig. 2). The inferior extremity of the tube 35 is connected by means of a clip 40 with a flexible

tube 41 through which passes a rod 42, and this tube and rod is again prolonged by another tube and rod of substantially the same construction, as shown in Fig. 15, the length of said tubes depending on the distance which separates the announcing device from the carriage provided at the bottom of the vehicle and the object of which will appear hereafter.

To the inferior surface of the engine or vehicle, between the front wheels, is secured a plate 43 in any suitable manner, to which plate a forked frame 44 is attached, said frame being substantially U-shaped (Figs. 16 and 20). Within this frame there is another frame 45 also U-shaped and pivotally attached to the extremities of the legs of the first frame 44 by means of a bolt or pin 46. Between the legs of the inner U-shaped frame 45 there is a rotatably mounted wheel 47, and a stop 48 is provided which permits the inner frame 45 to hang down for a certain distance within the frame 44. The inferior extremity of the connecting rod 42 rests upon the frame 45, and this disposition permits the rods 42 and 34 to be moved upwardly within their respective tubes and to operate the lever 32 of the announcing device.

Said lever 32 is provided with a projection 49 which engages the angular lever 50 shown in Fig. 14, and this lever 50 moves the pawl 51, both lever and pawl being pivotally mounted in a bracket fastened to the rear or bottom plate of casing 1. Said pawl 51 engages a flange 52 of the signaling plate of the announcing apparatus. This announcing apparatus comprises two guide rods 53, shown in Fig. 11, the extremities of which guide rods are fastened to the sides of casing 1. Slidably mounted on said guide rods is a signaling plate 54 divided into two fields the upper of which is painted in a white color and the lower in a red color. The inferior extremities of the guide rods 53 are connected by a plate 55, in the center of which rotates a numbered dial 56 fastened on top of a ratchet wheel 57, which ratchet wheel is rotated step by step by a pawl 58 fastened to the lower part of the signaling plate 54. A lever 59 provided with a spring 60 presses against the inferior part of the ratchet wheel 57 in order to permit the pawl 58 to engage only one tooth of the ratchet wheel 57 at a time. On the rear surface of the plate 54 there is a pin 61 which engages a spring 62 fastened to the inner side of the casing 1, said spring tending to move the plate 54 upwardly. One side of the plate 54 is furthermore provided with a stud 63 through which said plate may be moved downwardly by the action of a pin 64 mounted on the lever 25.

The lid or cover 2 of casing 1 comprises a metal collar screwed on top of casing 1, and

a circular glass plate painted so as to leave only a transparent aperture for one of the fields of the signaling plate 54, and another aperture for a numeral of the numbered dial 56.

The operation of the device is as follows:

The device is prepared for emergencies by pulling the handle 27 downwardly. This movement operates the lever 25 which rotates the toothed segment 24 and said segment in turn winds up the spring contained in casing 3, after which the projection 30 of said segment is engaged by the pawl 29 and the segment held in a downward position. At the same time the pin 64 pulls down the signaling plate 54, bringing into view the white field on the transparent aperture of the cover of casing 1. In this position of the device the valve of the air 20 brake is closed.

In order to operate the device, a buffer block is disposed between the rails of the oncoming train on all the places where a stopping of the train is required, some forms 25 which said buffer block may take being illustrated in Figs. 18, 19 and 20. When the wheel 47 of the frame 45 passes over one of said buffer blocks, said frame 45 is moved upwardly transmitting this movement to the 30 connecting rod 42. This rod in turn pushes upwardly the buffer base plate 38 which moves the rod 34 in the same direction. The superior extremity of this rod operates the lever 32, and the projection 49 of said lever 35 disengages the pawl 51 from the flange of the signaling plate 54, which plate is pulled upwardly by the spring 62, bringing the red field into view on the cover of the device. At the same time the pawl 58 moves the dial 40 56 and a new recording number appears on the lid of the casing 1. The other arm of the lever 32 disengages the pawl 29 from the segment 24, which segment moves upwardly 45 through the tension of the spring, and this spring rotates at the same time the gear wheel 4. This gear wheel, the movement of which is regulated by the regulator 14, rotates the gear wheel 15 which opens the valve 21 of the air brake. The passage of 50 the air being free, the whistle 23 is blown, the air brakes applied, and the train is brought to a stop. Pulling again the handle 47, as described above, leaves the device 55 ready for the next operation.

It is obvious that in case of danger a beam, stone or any other suitable obstacle 60 may be thrown between the rails in order to operate the device. I am also aware that the carriage consisting of two U-shaped frames with a wheel between the inner frame may be varied as may best be suited to different conditions, as for instance in case of heavy snow drifts, and generally I do not purpose limiting the patent granted other-

wise than necessitated by the prior art, as 65 various details of construction may be varied through a wide range without departing from the principles of this invention and within the scope of the appended claims.

What I claim is:—

1. In train signaling apparatus, a valve, a 70 spring motor to operate the valve, winding means for the motor including a pivotally mounted element, a lever to move said element in the required direction to wind the motor spring, a signaling element actuated by said lever, a trip element to hold said pivotally mounted element and thereby prevent operation of the motor, and train operated means to actuate the trip element. 80

2. In train signaling apparatus, a valve, a 85 spring motor to operate the valve, winding means for the motor including a pivotally mounted element, a lever to move said element in the required direction to wind the motor spring, a signaling element movable by said lever to one position, a spring to move said signaling element to another position, a trip element to hold said pivotally mounted element and thereby prevent operation of the motor, and train operated means to actuate the trip element. 90

3. In train signaling apparatus, a valve, a 95 spring motor to open the valve, winding means for the motor including a pivotally mounted element, a lever to move said element in the required direction to wind the motor spring, a signaling element movable by said lever in one position, a detent to hold said signaling element in such position, a spring to move said signaling element to another position, a trip element to hold said pivotally mounted element and thereby prevent operation of the motor, and train operated means to actuate the trip element, said trip element being also arranged to release the detent from the signaling element. 100

4. In train signaling apparatus, a valve, 110 a spring motor to operate the valve, winding means for the motor including a pivotally mounted element, a lever to move said element in the required direction to wind the motor spring, a signaling element movable by said lever to one position, a recording mechanism actuated by said signaling element, a spring to move said signaling element to another position, a trip element to hold said pivotally mounted element and thereby prevent operation of the motor, and train operated means to actuate the trip element. 115

In testimony whereof I affix my signature in presence of two witnesses.

FERNANDO ROQUE ELIZONDO.
